SHEET FEEDING AND OVERLAPPING MECHANISM

Frederick Renz, Forest Hills West, N. Y.

Application March 10, 1938, Serial No. 195,103

6 Claims. (Cl. 271—76)

This invention relates generally to sheet feeding apparatus and broadly comprehends an improved mechanism for receiving and overlapping sheets which are fed singly and in spaced relation thereto and for presenting the same in their overlapped relation to the receiving box of a layboy or other sheet stacking apparatus so as to obviate any possibility of collision between the trailing edge of a preceding sheet and the leading edge of a following sheet as the same enter the receiving box of the layboy.

The invention broadly resides in an improved mechanism of the indicated character and for the purpose specified wherein means is provided for arresting the sheets in their movement so that a preceding sheet, while so arrested, is overlapped by an adjacent following sheet and the overlapped arrangement of the sheets maintain until they enter the layboy receiving box.

More particularly the invention contemplates a sheet arresting means which is controlled by the sheets themselves and wherein each sheet actuates the arresting means to stop itself and wherein a preceding sheet which has been arrested is released by a following sheet as it reaches a predetermined point.

The invention, furthermore, embodies means for so conveying the sheets subsequent to their overlapping as to maintain proper alignment of their side edges as they enter the layboy receiving box thereby insuring an even jogging of the sheets therein.

The invention, furthermore, includes means for regulating the pressure of the sheet arresting means so that the sheets are not abruptly brought to a stop thereby avoiding buckling of the rear portion of the sheet being arrested and causing the same to lie flat on the conveyor means to prevent collision of the following sheet during the initial overlapping thereof.

Other objects of the invention reside in the provision of a sheet overlapping mechanism which is positive in its action, comparatively simple in its construction and mode of operation and which may be economically manufactured and installed.

With the above enumerated and other objects in view, the invention is set forth in greater detail in the following specification, illustrated in the accompanying drawings and particularly pointed out in the appended claims which cover variations and modifications not specifically disclosed, but which fall within the scope of the invention.

In the drawings:

Fig. 1 is a diagrammatic plan view illustrating a sheet overlapping and feeding mechanism constructed in accordance with the invention and showing the same interposed between a layboy 5 and a feed from a source of supply of sheets.

Fig. 2 is a diagrammatic side view thereof.

Fig. 3 is a detail perspective view of the means for controlling the sheet arresting means.

Fig. 4 is an enlarged fragmentary diagrammatic side view with parts shown in section illustrating the sheet arresting means in its active position.

Fig. 5 is a similar view showing a sheet on the feeding conveyor in engagement with the switch arm and breaking the circuit to render the sheet arresting means inactive.

Referring to the drawings by characters of reference, 10 designates a series of conveyor cords upon which are fed, from a source of supply, a 20 succession of sheets S which are spaced apart longitudinally of the conveyor cords as the upper leads thereof travel in the direction of the arrows towards and around the driven peripherally grooved roll 11 which is mounted to turn on a 25 transverse axis. Superimposed upon the roll 11 in staggered relation to the conveyor cords 10, are a series of idler wheels 12 having rubber or other suitable yieldable treads 13 which bear upon the periphery of the driven roll 11 to impart 30 turning motion to the wheels. The wheels 12 are secured to an idler shaft 14 mounted for rotation on a transverse axis parallel to the axis of rotation of the roll 11 and said shaft has secured thereto pulley sheaves 15 which, together with 35 the shaft 14, are rotated in unison with the wheels 12 by their frictional contact with the roll 11.

A guide plate 16 having a downwardly curved forward edge 17 is supported at the transverse 40 medial portion of the roll 11 and is located within a medial peripheral groove 18 formed on the roll so that its upper surface is flush with the upper portion of the periphery of the roll 11. The guide plate is provided with a central longitudinal 45 notch 19 which opens through the rear edge and extends forwardly therefrom.

The overlapping mechanism or unit includes a pair of driven conveyor rolls 20 and 21 which are mounted to turn on transverse axes parallel to 50 the axis of the roll 11 and are spaced apart longitudinally of the mechanism or unit with the upper portion of the peripheries of the rolls 20 disposed in a horizontal plane below the plane of the upper leads of the conveyor cords 10. The 55

rolls 20 and 21 have trained thereabout endless conveyor tapes 22, the upper leads of which are adapted to receive thereon the sheets S as they leave the roll 11 and which are fed longitudinally beyond the roll by the action of the conveyor cords 10 and the feeding action of the idler wheels 12 impinged upon and rotated by the periphery of the roll 11.

In order to hold down and guide the leading edges of the sheets downwardly onto the conveyor tapes 22, overhead guide cords 23 are provided which are trained around the pulley sheaves 15 on the idler shaft 14 and around idler pulley sheaves 24 which are rotatably mounted on a transverse axis such as the rock shaft 25, the lower leads of the guide cords 23 being inclined downwardly from the pulley sheaves 15 to the idler pulley sheaves 24 so that said guide cords 23 extend longitudinally of and above the upper leads of the conveyor tapes 22.

A guide roll 26 mounted for rotation on a transverse axis is interposed between the conveyor rolls 20 and 21 and is so positioned that the upper portion of its periphery is in a plane slightly above the plane of the upper portions of the peripheries of the rolls 20 and 21 so that the upper leads of the conveyor tapes 22 incline slightly from the roll 20 to the roll 26 and decline slightly from the roll 26 to the roll 21 thereby causing the sheets as they are conveyed on the upper leads of the conveyor tapes 22 to assume a longitudinally angulated position for a purpose which will be hereinafter set forth.

A fixed non-rotary transverse rod 27 extends across the overlapping unit or mechanism beneath the upper leads of the conveyor tapes 22 and said rod has secured thereon a plurality of transversely spaced abutments 28 of rubber or other yieldable material which are staggered with reference to the conveyor tapes and the upper surfaces of which are disposed slightly above the upper surfaces of the upper leads of said conveyor tapes to allow free running of the tapes when the sheet is arrested.

The rock shaft 25, in addition to serving as a mounting for the idler sheaves 24 has secured thereto and projecting therefrom a plurality of stop fingers 29 corresponding in number to the number of abutments 28 and the free terminals 30 of which overlie the abutments 28.

The rock shaft also has secured thereto a radially projecting actuating arm 31 which is connected by a pin 32 to a vertically disposed shift bar 33 which is in turn adapted upon shifting upwardly to rock the shaft 25 in a direction to raise the stop finger terminals 30 with reference to the abutments 28 and upon downward shifting movement to engage the stop finger terminals 30 with the abutments 28. The bar 33 is shifted upwardly by means of a coiled contractile spring 34 which is connected at its lower terminal with the bar and anchored at its upper terminal to an overhead support 35. The lower end of the shift bar 33 is connected to the movable core 36 of a solenoid 37 which when energized, shifts the bar 33 downwardly against the action of the spring 34 to rock the shaft 25 in a direction to impinge the stop finger terminals 30 against the abutment elements 28.

The solenoid 37 is arranged in an electrical circuit 38 including a source of supply 39 and a switch 40 which controls the opening and closing of the circuit 38 to energize and de-energize the solenoid 37. The switch 40 is provided with a fixed contact 41 and a movable contact 42 and

the movable contact is carried by an actuating arm 43 which is fulcrumed as at 44 and the terminal of which arm extends through the slot 18 of the guide plate 16 and into a peripheral groove 45 in the roll 11 so that the switch controlling arm 44 is disposed in the path of movement of the sheets S as they are conveyed by the conveyor cords 10 over the upper portion of the periphery of the roll 11 and over the upper surface of the guide plate 16, it being apparent that the sheets S as they move over the guide plate, will lift and retain the switch control arm 43 in an elevated position and when so elevated the movable contact 42 will be out of engagement with the fixed contact 41 of the switch. It will be likewise apparent that when no sheet is in a position to retain the switch arm 43 in its upper position, the same will drop by gravity to its lower position so as to cause the movable contact 42 to engage the fixed contact 41, thus closing the circuit 38 to the solenoid 37.

In addition to the conveyor tapes 22, the overlapping mechanism has extending longitudinally thereover a series of upper cords 50, the lower leads of which overlie the upper surfaces of and move in the same direction as the sheets. The lower leads of the conveyor cords 50 are impinged upon the tapes 22 at the portions thereof which are elevated by the roll 26 so as to exert a pressure on the sheets in the region thereof which is passing over the roll 26.

The overhead cords 50 are trained around a suitable supporting idler, not shown, and around the upper roll 51 of the layboy 52 which is of any of the well known types having a receiving box 53 and a declining guide surface 54. The layboy is also provided with a lower intake roll 55 between which and the intake wheels 56 the sheets S are received and fed thereby into the receiving box after passing over the inclined guide surface 54.

In use and operation, as the leading edge of the first sheet S engages the switch arm 43 and raises the same, the circuit 38 is broken thereby de-energizing the solenoid 37 to permit the spring 34 to raise the stop finger terminals 30 out of engagement with the abutments 28. As the sheet enters the overlapping unit and is advanced and guided by the overhead cords 23 onto the conveyor tapes 22 to a position between the separated stop finger terminals 30 and the abutments 28, it will be automatically arrested and prevented from further longitudinal movement towards the layboy as soon as its rear or trailing edge has cleared the switch arm terminal 43 due to the fact that the switch arm will drop and close the circuit 38 thereby energizing the solenoid. It is apparent that the energized solenoid will pull the core 36 thereof downwardly together with the shift bar 33 to impinge the stop finger terminals 30 against the abutments 28 thus clamping the sheet therebetween. It should, however, be noted that the trailing edge of said sheet will at this time, due to momentum, have passed beyond the roll 11 and dropped down onto the conveyor tapes 22 so that the trailing edge is in a plane below the plane of the upper leads of the conveyor cords 10. As soon as the leading edge of the second or following sheet S engages with and raises the switch arm 43 to break the circuit, the solenoid 37 will be de-energized thus allowing the spring 34 to move the shift bar 33 upwardly for releasing the preceding sheet. It should here be noted that the conveyor tapes 22 are driven at a considerably lesser rate of speed than the conveyor 75

tapes 10 and in practice it has been found that the ratio of three to 1 operates satisfactorily, that is, the conveyor cords 10 travel at a rate of speed three times that of the conveyor tapes 22. It thus follows that when the leading edge of the second or succeeding sheet actuates the switch to break the circuit, the preceding sheet will be released and will start to travel at one-third the rate of speed of the following sheet so that the following sheet with its leading edge elevated above the first or preceding sheet will gain upon and overlap the trailing edge of the first or preceding sheet, while continuing to increase the overlap due to the difference in the rate of speed at which it is fed until its trailing edge passes beyond the switch arm and again causes the circuit 38 to be closed for energizing the solenoid. At this time, the trailing edge of the second sheet will, due to momentum, have passed beyond the roll 11, while the leading portion thereof has advanced to a position between the separated stop finger terminals 30 and abutments 28 so that said second sheet will be gripped and arrested in its movement, while the trailing edge of the first or preceding sheet will have been conveyed beyond the stop fingers. Immediately following this, the leading edge of the third sheet will engage and raise the switch arm to break the circuit thus releasing the second sheet while still in overlapping relation to the first sheet and the same will then be conveyed together in overlapped relation upon the conveyor tapes 22. The operation is repeated on each succeeding sheet so that the sheets are uniformly overlapped a predetermined distance and are conveyed on the tapes 22 between the intake roll 55 and the intake wheels 56 of the layboy and presented to the layboy in their overlapped relation.

In order to maintain a proper alignment of the side edges of the sheets during and subsequent to their overlapping and to insure their entering the layboy with their side edges properly aligned whereby to cause even jogging of the sheets in the receiving box, the sheets are caused to assume a longitudinally angulated position by the longitudinal angulations of the upper leads of the conveyor tapes 22. This resists any tendency of the sheets to become misaligned at their side edges during and subsequent to the overlapping operation. Means is provided for regulating the pressure of the stop fingers against the abutments 28 so that the sheets will not be abruptly stopped and to thereby avoid buckling of the rear portion of the sheets as they are arrested. This means 50 consists of the employment of set screws 60 threaded through the collars 61 which carry the stop fingers 29 and set screw 62 on the collar 63 which carries the actuating arm 31. Either of the fingers may be adjusted individually or the collar of the actuating arm adjusted to accomplish this end.

What is claimed is:

1. A mechanism for overlapping and presenting sheets in overlapped relation to a layboy comprising means for conveying the sheets to the layboy, means for feeding the sheets in spaced relation to said conveyor means, said conveyor means being disposed in a plane below and operated at a lesser speed than the feeding means, means for arresting the movement of a sheet on the conveyor means so that said sheets are overlapped during the arresting thereof on the conveyor means while the conveyor means continues to move to present previously overlapped sheets to the layboy, and means controlled by the sheets

for effecting the actuation of the sheet arresting means.

2. A mechanism for overlapping and presenting sheets in overlapped relation to a layboy comprising means for conveying the sheets to the layboy, means for feeding the sheets in spaced relation to said conveyor means, said conveyor means being disposed in a plane below and operated at a lesser speed than the feeding means, means disposed in the path of movement of the sheets on the conveyor means for arresting the movement of a sheet on the conveyor means so that said sheets are overlapped during the arresting thereof on the conveyor means while the conveyor means continues to move to present the previously overlapped sheets to the layboy, and means disposed in the path of movement of the sheets on the feeding means and controlled by the sheets for effecting the actuation of the sheet arresting means.

3. A mechanism for overlapping and presenting sheets in overlapped relation to a layboy comprising means for conveying the sheets to the layboy, means for feeding the sheets in spaced relation to said conveyor means, said conveyor means being disposed in a plane below and operated at a lesser speed than the feeding means, means for arresting the movement of a sheet on the conveyor means so that said sheets are overlapped during the arresting thereof on the conveyor means, means controlled by the sheets as the same are fed from the feeding means to the conveyor means for effecting the actuation of the sheet arresting means, and means for maintaining the overlapped sheets in overlapped relation until they are fed into the layboy.

4. A mechanism for overlapping and presenting sheets in overlapped relation to a layboy comprising means for feeding the sheets in spaced relation, a longitudinal conveyor means driven at a lesser speed than the feeding means and disposed in a plane below the feeding means and between the feeding means and the layboy, means controlled by the sheets as the same are fed from the feeding means for effecting the arrestment of the movement of a sheet on said conveyor means so that adjacent sheets are overlapped, said latter means including a stop finger, electrically actuated means, and means disposed in the path of movement of the sheets on the feeding means and released by the sheets for rendering the electrically actuated means active to effect the moving of said stop finger into contact with the sheets on the conveyor means for arresting the same, and means for maintaining the sheets in overlapped relation as they enter the layboy.

5. A mechanism for overlapping and presenting sheets in overlapped relation to a layboy comprising means for feeding the sheets in spaced relation, a longitudinal conveyor means driven at a lesser speed than the feeding means and disposed in a plane below the feeding means and between the feeding means and the layboy, means for arresting the movement of each sheet on the conveyor means so that the same is overlapped by the following sheet subsequent to the arrestment thereof, said latter means including a stop finger, an electric circuit including an electro-magnet adapted when energized to render the stop finger active to arrest a sheet, and a gravity operated switch normally closing the circuit and having an arm disposed in the path of movement of the sheets on the feeding means and actuated when released by the sheets to effect

the closing of the electric circuit and the energizing of the electro-magnet.

6. A mechanism for overlapping and presenting sheets in overlapped relation to a layboy comprising means for feeding the sheets in spaced relation, a longitudinal conveyor means driven at a lesser speed than the feeding means and disposed in a plane below the feeding means and between the feeding means and the layboy, 10 a stop finger, an electric circuit including an electro-magnet adapted when energized to render the stop finger active to arrest a sheet as it is received upon the conveyor means, a gravity operated switch normally closing the circuit and having an arm disposed in the path of movement of

the sheets on the feeding means and actuated when released by the sheets to effect the closing of the electric circuit and the energizing of the electro-magnet, said arm being adapted to be raised by the succeeding sheet on the feeding means to effect the opening of the electric circuit and the de-energizing of the electro-magnet to thereby render the stop finger inactive and to release the arrested sheet so that the succeeding sheet is delivered to the conveyor means in overlapping relation with the released sheet, and means for maintaining the sheets in overlapped relation as they are presented to the layboy. 1

FREDERICK RENZ.
